UNITED STATES PATENT OFFICE.

JAMES B. VERNON, OF PAOLA, KANSAS.

DESIGN FOR A DENTAL-INSTRUMENT HOLDER.

SPECIFICATION forming part of Design No. 35,610, dated January 28, 1902.

Application filed November 7, 1901. Serial No. 81,505. Term of patent 14 years.

To all whom it may concern:

Be it known that I, JAMES B. VERNON, a citizen of the United States, residing at Paola, in the county of Miami and State of Kansas, have invented and produced a new and original Design for Dental-Instrument Holders, of which the following is a specification.

My invention relates to holders or handles for dental instruments of that class which are adapted to be held and manipulated or directed in their work by hand; and my object is to produce a new and original design for the same which is both useful and ornamental.

15 In the accompanying drawings, Figure 1 is a side view, and Fig. 2 an end view, of a holder or handle embodying my design.

As shown in the drawings, the leading or material feature of the design resides in a handle embracing a long and a short end and an elongated diametric enlargement between and in longitudinal alinement with said ends and provided with a swelling at its end contiguous to the short end of the handle.

20 Minor features of the design reside in the cylindrical form of the long and short ends of the handle, in the tapering prolongation of the latter, in the triangular form in cross-section of the elongated enlargement connecting the ends of the handle, and in the concaved or hollowed surface of the swelling

of said enlargement; also, in the milled or roughened surface of said swelled portion and in the V-shaped points of said roughened or milled surface, which appear on the sides of 35 the triangular portion and are disposed toward the long end of the handle.

Referring to the drawings in detail, 1 2 designate the long and the short ends of the handle, and 3 the tapering prolongation of the 40 short end thereof.

4 designates the diametric enlargement, triangular in cross-section, connecting and in longitudinal alinement with said ends of the handle.

45 5 designates the swelled portion of the enlargement, the same having a milled or roughened concaved or hollowed surface and V-shaped points 6 upon the flat faces of the triangular enlargement.

50 Having thus described the invention, what I claim as new, and desire to secure by Letters Patent, is—

The design for a dental-instrument holder, substantially as herein shown and described. 55

In testimony whereof I affix my signature in the presence of two witnesses.

JAMES B. VERNON.
